(57) CLAIM

The ornamental design for a gaming cabinet, as shown and described.

DESCRIPTION

FIG. 1 is a front perspective view of a gaming cabinet; FIG. 2 is a reverse front perspective view of the gaming cabinet shown in FIG. 1;

FIGS. 3 and 4 are substantially mirrored images of left and right side views of the gaming cabinet shown in FIG. 1; FIG. 5 is a front view of the gaming cabinet shown in FIG. 1; and,

FIG. 6 is a top view of the gaming cabinet shown in FIG. 1. The ornamental design which is claimed is shown in solid lines in the figures. Any broken lines in the figures are for illustrative purposes only and form no part of the claimed design.
